S. WATSON.
MARKER FOR CORN PLANTERS.
APPLICATION FILED DEC. 13, 1920.

Patented Dec. 6, 1921.

G. J. Baker.

WITNESS:

Brother Watson,
INVENTOR
BY *Victor J. Evans*
ATTORNEY

UNITED STATES PATENT OFFICE.

STROTHER WATSON, OF GALLATIN, TENNESSEE.

MARKER FOR CORN-PLANTERS.

1,399,677.

Specification of Letters Patent.

Patented Dec. 6, 1921.

Application filed December 13, 1920. Serial No. 430,310.

To all whom it may concern:

Be it known that I, STROTHER WATSON, a citizen of the United States, residing at Gallatin, in the county of Sumner and State 5 of Tennessee, have invented new and useful Improvements in Markers for Corn-Planters, of which the following is a specification.

This invention relates to a marker for corn planters, and the invention consists in the 10 novel construction, combination and arrangement of elements hereinafter described and claimed.

In the drawings, Figure 1 is a top plan view showing the marking device applied to 15 a planter, and Fig. 2 is a fragmentary view, in section, showing one of the marking elements and the manner of mounting this device.

A planter of standard type includes seed- 20 ing devices 10, the usual valves of which are controlled by valve rod 12. Shaft 14 carries a device 15 coöperating with an element 16 on the valve rod, and also carries a ratchet wheel 35, operated by suitable means 25 for imparting partial rotation to shaft 14 in adjusting the position of the markers.

The main shaft 20 carries ground wheels 21, and mounted on this shaft is a sprocket wheel 22, driving chain 23, the chain passing 30 around sprocket wheel 24, shaft 14 of the marking device. A smaller sprocket wheel 25 may be used for producing a drive at a higher speed.

Radially connected with each end of the 35 shaft 14 is a T-connection having a bore 27 through which arm 28 of the marking device passes. Springs 29 encircle arm 28 on opposite sides of the T-connection and their outer ends being properly retained the arm 40 is permitted to move transversely of the shaft 14, with the result that the marking devices are allowed to yield in passing over uneven ground.

Each marking device comprises a cup-shaped element 30, connected by a brace 31 45 with arm 28, this brace comprising a central apertured element and a plurality of outwardly extending arms as shown. The cup-shaped device 30 is especially effective in making a clear mark. 50

Mounted on the shaft 14 is a ratchet wheel 35 engaged by a pawl 36 mounted on lever 37, or more definitely speaking between elements 37' constituting apertured forked ends, these members 37' being swung from 55 shaft 14 on opposite sides of the ratchet wheel.

From the foregoing it will be observed that owing to the simplicity of the device and the direct and positive connection between the operative elements, reliability in operation is assured. While I have referred to certain minor details of construction, it is obvious that changes in such details may be made within the scope of the appended 65 claims.

What is claimed is:—

1. A marking device for a planter, comprising a cup-shaped element, an apertured brace connected therewith and extending 70 across the open end of the cup, and a supporting member, said apertured brace permitting of the mounting of the cup on the supporting member.

2. In a device of the class described, a 75 shaft and means for driving the shaft, arms mounted perpendicularly of the shaft at opposite ends thereof, and cup-shaped marking devices mounted on the arms and having their open ends toward the shaft, each 80 marking device including a transverse brace through which the shaft passes, said brace acting as a mounting device.

In testimony whereof I affix my signature.

STROTHER WATSON.
